UNITED STATES PATENT OFFICE.

JESSE DITSON, OF LITTLETON, COLORADO, ASSIGNOR TO INGERSOLL-RAND COMPANY,
OF JERSEY CITY, NEW JERSEY, A CORPORATION OF NEW JERSEY.

DOUBLE-DRUM HOIST.

1,417,041.

Specification of Letters Patent. Patented May 23, 1922.

Application filed July 20, 1921. Serial No. 486,098.

To all whom it may concern:

Be it known that I, JESSE DITSON, a citizen of the United States, and a resident of Littleton, Arapahoe County, Colorado, have invented a certain Double-Drum Hoist, of which the following is a specification accompanied by drawings.

This invention relates to hoists, but more particularly to a self-contained double drum hoist driven by a single motor which may be a fluid pressure reversible motor. A hoist of this type is suitable for use in many kinds of work, in mines, factories, ship yards and other places, for hauling, lifting, and other purposes.

Such a hoist may be mounted on a column, cross bar or other support in various positions, and is ordinarily subjected to hard and rough usage, may be given little attention and frequently exposed to the elements, so that it should be rugged and furthermore so constructed that complicated parts which are liable to break or get out of order are avoided.

The objects of this invention are to construct a hoist of the double drum type having a strong and firmly braced frame, including a motor at one end and a gear box at the other, the parts of which can be readily assembled and disassembled, permit convenient and easy accessibility to the driving connections, reduce the number of parts, cheapen the cost of manufacture and produce a hoist which is rugged and will withstand the rough usage to which it may be subjected.

Further objects of the invention will hereinafter appear and to all of these ends the invention consists of the features of construction, arrangements of parts and combinations of elements substantially as fully described and claimed in this specification and shown in one of its preferred forms in the accompanying drawings in which—

Figure 1 is a horizontal sectional plan view of the hoist;

Figure 2 is a longitudinal sectional elevation on the line 2—2 of Figure 1 through the center of the hoist looking in the direction of the arrows;

Figure 3 is a transverse sectional view through the gear box of Figure 1 looking in the direction of the arrows;

Figure 4 is an end elevation of the motor end of the hoist partly broken away and 55 partly in transverse section, and

Figure 5 is a detail sectional elevation of the motor valve showing the valve in a different position from that indicated in Figure 4.

Referring to the drawings, the base plate A of the hoist is provided with the clamping member B and the saddle clamp C having the clamping bolts D for clamping the hoist to a column, cross bar or other support. 65 A supporting frame E is mounted in upright position at one end of the base plate as by means of the bolts F, and another supporting frame in the form of a gear box G is likewise mounted in upright position 70 at the opposite end of the base plate A as by means of the bolts H. A removable cover plate J is secured to the gear box G as by means of the bolts K in order to permit ready accessibility to the driving connections of the hoist which are preferably shown in the form of gearing.

A central driving shaft L is mounted in the roller bearing O in the frame E and in the bearing sleeve P in the gear box J, and 80 is preferably covered and protected by the sleeve Q. The driving shaft L is connected to be driven by a motor dismountably connected to the frame E and as shown the crank disk R having the crank pin S is 85 connected by means of the roller bearing T to the piston U of a fluid pressure motor of the Dake or so called "square piston type", as a motor of this type has been found to be particularly adaptable for a self-contained hoist. The frame E of the hoist forms the inner or back head of the motor cylinder casing V which is in the form of a flat rectangular frame open at front and back. In a motor of the Dake type the piston U has an up and down motion in the piston frame W which reciprocates back and forth in the cylinder casing V on the gib X adjustable by means of the screws Y.

The front cylinder head Z is removably 100 secured to the cylinder casing V as by means of the bolts a which also hold the front head Z and cylinder casing V to the frame E.

Motive fluid is supplied to the motor at the inlet b and exhausted at the outlet c and 105 the distribution of motive fluid is controlled

by a suitable manually operated reversing valve *d* slideable in the valve chest *e* formed in the cylinder head *Z*. The valve *d* is provided with the heads *f*, *g* and *h* controlling 5 ports and passages in the valve chest *e* leading to the motor. A rack *j* on the valve engages a pinion *k* to which a valve lever *o* is connected by means of which the valve is manipulated. Springs *p* between the ends 10 of the valve and the plugs *q* oppose movement of the valve in either direction.

Without describing the construction of the motor more fully since the details of the motor form no part of the present invention, and the motor is of a well known type, it will be sufficient to state that with the valve *d* in the position shown in Figure 4, motive fluid from the inlet *b* passes to the 15 passage *r* in the valve chest *e* and thence to the motor while the exhaust from the motor passes through the port *s* in the valve chest and out through the exhaust port *t* as indicated by the arrows in Figure 4. When the 20 position of the valve is reversed in order to reverse the motor as indicated in Figure 5, the motive fluid from the inlet *b* enters the valve chest at the passage *r* and passes to the motor through the port *s* while the exhaust from the motor enters the valve chest 25 at the port *u* and exhausts through the port *t*. A suitable oiling device *v* is connected to the valve chest for carrying oil into the motor, and an oiling device *w* on the supporting frame *E* supplies oil to the driving 30 shaft bearing.

The advantage of constructing the cylinder casing *V* of the motor as shown and described resides in the fact that the internal parts of the cylinder casing may be more 40 readily machined and the frame *E*, cylinder casing *V*, and cylinder head *Z* may be readily assembled and disassembled.

Drum bearings *x* which also serve to space the frame *E* and gear box *G* at a given distance apart, and brace the motor frame, are supported between the frames at each side of the driving shaft *L*. The drum bearings may be formed with shoulders *y* engaging the boxes *z* in the frame *E* and gear box *G* 45 respectively and bolts 2 passing through the drum bearings *x* serve to hold the parts together and securely brace the hoist frame.

Drums 3 and 4 are mounted to rotate upon the drum bearings *x* and a rope or cable 5 may have one end 6 connected to the drum 3 by means of the screw 7 and the other end 8 connected to the drum 4 by the screw 9 or other suitable devices the cable being wound on the drums in opposite directions, so that 55 one drum is a haulage drum and the other a tail rope drum both rotating in the same direction. Means are provided for connecting one drum or the other at will to be driven by the driving shaft *L* and the functions of the drums depend upon the direction 60

of rotation of the driving shaft to which rotation is imparted by the motor and also depend upon the adjustment of the controlling device for connecting one drum or the other to the driving shaft.

The driving shaft *L* is provided with the driving pinion 10 keyed thereto and intermediate gears 11 and 12 which do not engage the driving pinion, are mounted on the shafts 13 and 14 of the intermediate pinions 15 and 16 which mesh with the internal gears 17 and 18 of the drums 3 and 4 respectively. The intermediate pinion shafts 13 and 14 rotate in the ball bearings 19 and 20 in the gear box *G* and in the ball bearings 21 and 22 in the gear box cover plate *J*. A shiftable pinion 23 suitably mounted to rock about the center of the driving shaft *L* is provided for throwing either one of the intermediate gears 11 or 12 into driving connection with the driving pinion 10 and for this purpose a rocking frame 24 is pivoted at one side of the driving pinion 10 on the driving shaft bearing *P* and at the other side of the pinion 10 upon the bearing sleeve 25. The shaft 26 of the shiftable pinion 23 is carried in the rocking frame 24. A hand lever 27 is suitably clamped to an extension 28 on the rocking frame 24 by means of the bolt 29, and a spring latch 30 operated 35 by a handle grip 31 pivoted at 32 to the handle cooperates with the teeth 33 on the segment 34 for locking the rocking frame 24 in any desired position. An oil cup 35 closes the end of the tubular extension 28 on the 40 rocking frame 24 and a suitable oiling device 36 may be provided on the gear box *G*.

The drums are preferably provided with brakes 37 and 38 on the drum flanges 39 and 40. The brakes are preferably both at the same 45 ends of the drums so that brake levers 41 and 42 may conveniently be arranged side by side at the same end of the machine below one of the drums in position to be grasped by the operator. A brake rod 43 extending transversely across the machine beneath the drums is suitably mounted on the base plate *A* in the lugs 44 and the ends 45 of the brake 38 are connected to the brake nuts 46 and 47 traveling on the reversely 50 screw threaded portions 48 and 49 of the brake rod. Similarly the ends 50 of the brake 37 are connected to the nuts 51 and 52 traveling on the reversely screw threaded portions 53 and 54 of a sleeve 55 rotatable 55 on the brake rod 43. The brake lever 41 for the drum 3 is connected to the sleeve 55 while the brake lever 42 for the drum 4 is connected to the brake rod 43. The brakes are tightened or loosened in an obvious 60 manner by rotating the levers and the brake rod 43 and brake sleeve 55.

In the operation of the hoist let it be assumed that the motor is imparting rotation to the driving shaft *L* in a given direction 65

as for instance clockwise, as Figure 3 is viewed, and that the shiftable change gear pinion 23 has been moved into engagement with the intermediate gear 11 which is connected to drive the drum 3 by means of the intermediate pinion 15 and internal gear 17. The drum 3 becomes the haulage or lifting drum and is driven in the same direction as the driving shaft L. The tail rope drum is an idle drum in such case, permitting the rope or cable to unwind but will be rotated in the same direction as the drum 3. The conditions are merely reversed and both drums continue to rotate in the same direction as the driving shaft L when the change gear pinion 23 is shifted from the intermediate gear 11 into engagement with the intermediate gear 12. The direction of rotation of the drums is reversed by reversing the motor and imparting rotation to the driving shaft L in a reverse direction.

I claim:

1. A double drum hoist, comprising a base plate, a supporting frame mounted in upright position at one end of the base plate, a gear box mounted in upright position at the opposite end of the base plate, a removable cover plate for said gear box, a central driving shaft having bearings in said frame and gear box, a reversible fluid pressure motor secured at the outside of said supporting frame and operatively connected to drive said driving shaft in either direction, drum bearings supported by the said frame and gear box at each side of the central driving shaft and maintaining the outer portions of the frame and gear box in spaced relation, bolts passing through the drum bearings for holding the parts together, drums rotatably mounted on said drum bearings, and driving connections mounted in the gear box between the driving shaft and drums including shiftable means for connecting the driving shaft to one or the other of the drums.

2. A double drum hoist, comprising a base plate, a supporting frame mounted in upright position at one end of the base plate, a gear box mounted in upright position at the opposite end of the base plate, a central driving shaft having bearings in said supporting frame and gear box, a removable cover plate for said gear box, a reversible fluid pressure motor secured over the end of the driving shaft against the outside of said supporting frame, said motor being operatively connected to drive said driving shaft in either direction, tubular drum bearings supported in the supporting frame and gear box at each side of the driving shaft, through bolts passing through said drum bearings for holding the frame and gear box together, drums rotatably mounted on said drum bearings, driving connections mounted in said gear box for the driving shaft and for each

of the drums, and shiftable means for connecting either one or the other of said drums to be driven by the driving shaft.

3. A double drum hoist, comprising a base plate, a supporting frame mounted in upright position at one end of the base plate, a gear box mounted in upright position at the opposite end of the base plate, removable cover plate for said gear box, a reversible fluid pressure motor 70 supported at the outside of the said supporting frame, a central driving shaft having bearings in said frame and gear box said motor being operatively connected to drive said driving shaft in either direction, spacing 75 sleeves forming drum bearings supported in the frame and gear box at each side of the driving shaft, bolts passing through said drum bearings for holding the parts together, drums rotatably mounted on said 80 drum bearings, a driving pinion on the driving shaft, intermediate gears mounted in the gear box and connected to drive the drums respectively, an intermediate pinion mounted in the gear box meshing with the driving 85 pinion and shiftable into and out of mesh with one or the other of the said intermediate gears, and a hand operated lever outside of the gear box connected to shift said intermediate pinion to drive one or the other of 90 said drums.

4. A double drum hoist, comprising a base plate, a supporting frame mounted in upright position at one end of the base plate, a gear box mounted in upright position at 100 the opposite end of the base plate, a removable cover plate for said gear box, a central driving shaft having bearings in said frame and gear box, a reversible fluid pressure motor secured at the outside of said supporting frame said motor being operatively connected to drive said driving shaft in either direction, drum bearings supported by the said frame and gear box at each side of the central driving shaft in maintaining the 105 outer portions of the frame and gear box in spaced relation, bolts passing through the drum bearings for holding the parts together, drums rotatably mounted on said 110 drum bearings, driving connections mounted in the gear box between the driving shaft and drums including shiftable means for connecting the driving shaft to one or the other of the drums, a brake for each of said drums, hand operated brake levers for said brakes 115 located side by side at one end of the hoist below one of the drums, and operative connections between said brake levers and the brakes respectively.

5. A double drum hoist, comprising a base 125 plate, a supporting frame mounted in upright position at one end of the base plate, a gear box mounted in upright position at the opposite end of the base plate, a central driving shaft having bearings in said supporting 130

frame and gear box, a removable cover plate for said gear box, a reversible fluid pressure motor secured over the end of the driving shaft against the outside of said supporting frame, an outer head secured to the motor cylinder said motor being operatively connected to drive said driving shaft in either direction, tubular drum bearings supported in the supporting frame and gear box at each side of the driving shaft, through bolts passing through said drum bearings for holding the frame and gear box together, drums rotatably mounted on said drum bearings, driving connections mounted in said gear box for the driving shaft and for each of the drums, shiftable means for connecting either one or the other of said drums to be driven by the driving shaft, a brake for each of said drums, hand operated brake levers for said brakes located side by side at one end of the hoist below one of the drums, and operative connections between said brake levers and the brakes respectively.

6. A double drum hoist, comprising a base plate, a supporting frame mounted in upright position at one end of the base plate, a gear box mounted in upright position at the opposite end of the base plate, a removable cover plate for said gear box, a reversible fluid pressure motor

removably supported at the outside of the said supporting frame, a central driving shaft having bearings in said frame and gear box said motor being operatively connected to drive said driving shaft in either direction, spacing sleeves forming drum bearings supported in the frame and gear box at each side of the driving shaft, bolts passing through said drum bearings for holding the parts together, drums rotatably mounted on said drum bearings, a driving pinion on the driving shaft, intermediate gears mounted in the gear box and connected to drive the drums respectively, an intermediate pinion mounted in the gear box meshing with the driving pinion and shiftable into and out of mesh with one or the other of the said intermediate gears, a hand operated lever outside of the gear box connected to shift said intermediate pinion to drive one or the other of said drums, a brake for each of said drums, hand operated levers for said brakes located side by side at one end of the hoist below one of the drums, and operative connections between said brake levers and the brakes respectively.

In testimony whereof I have signed this specification.

JESSE DITSON.
